US0D1059371S

(12) **United States Design Patent** (10) **Patent No.:** **US D1,059,371 S**
(45) **Date of Patent:** **** Jan. 28, 2025**

(54) **DISPLAY SCREEN OR PORTION THEREOF
WITH GRAPHICAL USER INTERFACE**

(71) Applicant: **HUAWEI TECHNOLOGIES CO., LTD.**, Guangdong (CN)

(72) Inventors: **Minhao Li**, Shanghai (CN); **Kaiqi Jiang**, Shanghai (CN)

(73) Assignee: **HUAWEI TECHNOLOGIES CO., LTD.**, Shenzhen (CN)

(**) Term: **15 Years**

(21) Appl. No.: **29/815,294**

(22) Filed: **Nov. 12, 2021**

(30) **Foreign Application Priority Data**

May 28, 2021 (CN) 202130324897.4

(51) **LOC (15) Cl.** **14-04**

(52) **U.S. Cl.**

Primary Examiner — Daniel J Domino

(57) **CLAIM**

The ornamental design for a display screen or portion thereof with graphical user interface, as shown and described.

DESCRIPTION

The single FIGURE is a front view of a display screen or portion thereof with graphical user interface showing our new design.

The dash-dot broken lines in the drawings illustrate the display screen or portion thereof and form no part of the claimed design.

1 Claim, 1 Drawing Sheet
